(57) **CLAIM**

The ornamental design for a head of electric vehicle charger, as shown and described.

DESCRIPTION

FIG. 1 is a perspective view of a head of electric vehicle charger showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is another perspective view thereof shown in environmental use.

The broken lines in the drawings show portions of the head of electric vehicle charger that form no part of the claimed design.

1 Claim, 9 Drawing Sheets
